OTHER PUBLICATIONS

Examination Report of Canadian Application No. 185866, Issued Apr. 10, 2020.

Primary Examiner — David G Muller*(74) Attorney, Agent, or Firm* — Cook Alex Ltd.(57) **CLAIM**

The ornamental design for a urinary catheter as shown and described.

DESCRIPTION

FIG. 1 is a perspective view of a urinary catheter, showing a first embodiment of the new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a bottom plan view thereof; and,

FIG. 7 is a top plan view of the thereof.

The broken lines showing parts of the drawings are included for the purpose of depicting use and environment, and form no part of the claimed design.
